UNITED STATES PATENT OFFICE.

FRANCIS H. SMITH, OF BALTIMORE, MARYLAND.

BRICK-MACHINE.

Specification of Letters Patent No. 11,753, dated October 3, 1854.

To all whom it may concern:

Be it known that I, FRANCIS H. SMITH, of Baltimore, in the State of Maryland, have invented certain new and useful Improvements in Machines for Making Bricks; and I do hereby declare the following to be a full, clear, and exact description of the same, reference being had to the accompanying drawings, making a part thereof, in which—

- 10 Figure 1, represents a side elevation. Fig. 2, represents an end elevation. Fig. 3, represents an isometrical view of the machine. Fig. 4, represents a plan or top view of the bed plate which is fitted onto the sills at the bottom of the clay box, and into the center of which the shaft is stepped, (as also of the screw), and through which the clay is forced into the molds as they (the molds) pass on the ways beneath. Fig. 5, represents a vertical section through the hub or step of the screw and plate, showing the wooden plug therein. Fig. 6, represents a top view of the sectional screw which forces the clay into the molds. Fig. 7, represents a front view of 15 one of the mold frames with a portion removed in order to show the movable or sliding bottoms of the molds, and the manner in which the brick is lifted out of the mold on said bottom by the vertical piston. Fig. 8, represents an end view of another method of 20 constructing the mold frame, the sides being elongated at the lower edge so as to embrace a plate which serves as a bottom to the whole frame said plate being made to slide on the ways, taking the mold along with it. Fig. 9, represents a top view of a broad knife, hung on pivots, to slice off the 25 surplus clay from the mold. Fig. 10, represents a top view of the dust box.
- 30 40 Similar letters where they occur in the several figures denote like parts.

The nature of my invention consists first, in the flat, square or triangular bar for pulverizing the clay. Also, the mode of stepping the shaft within the clay box, that is to say, the projecting hub on the bed plate with its wooden conical seat, in combination with the cavity in the stem of the screw, by means of which, the surrounding clay is excluded 45 from the step, to prevent the wear, and the screw brought down near the bed plate to wipe as near as possible, without contact—thus the throat of the screw gathers within itself a charge of clay which can not escape except through the openings of the bed plate

5 into the molds beneath. Also the open portable mold frame with a projecting flange, said mold resting on a single detached plate for a bottom, and so that when the mold is thrown on the floor, the brick does not at 60 the same time come in contact with the ground because the flanges interfere. This gives a concussion to the brick, just enough to give it a start, and it then slips easily from the mold.

65 To enable others skilled in the art to make and use my invention, I will proceed to describe the same with reference to the drawings.

A, represents the frame of the machine 70 which does not differ essentially from others in present use, and therefore requires no particular description.

B is a cylinder or shaft having on its periphery a series of teeth in a spiral form 75 (Fig. 2), which I call a crusher or lump breaker. It is placed in front of the machine, and within a hopper E, which has a passage leading into the clay box F (the sides of the box being removed in Fig. 1). 80

Directly under the crushed B, and also within the same hopper E, there is placed a second shaft G, formed either of a flat, square, or triangular bar i, which I term a pulverizer. The office of the crusher is to 85 break the lumps of clay into small particles, and the office of the pulverizer is to reduce the small particles to dust. The manner in which the crusher B, and pulverizer G, operate will be clearly seen in Fig. 2. The clay 90 is introduced into the hopper and thence passes down between the pulverizer, and the back of the hopper, and enters the clay box F. The object in having the teeth of the crusher B, placed around the shaft in a spiral form is to prevent several teeth acting upon a lump at the same time, as great power 95 would be required to drive the crusher if this were so. The spiral form allows one tooth only to act upon the clay at the same time. 100 The crusher B, should move about one hundred revolutions, and the pulverizer G, about six hundred revolutions per minute, which reduces the clay into dust. In this state on entering the clay box F, it unites immediately with a jet of water I, brought through a hose from a reservoir.

J, is a vertical shaft placed in the center of the clay box F, having thereon at its lower end a segment of a large screw thread D (a 110

separate view of which is seen in Fig. 6). Directly above the screw thread, and on the same shaft J, are placed a series of knives K, (Figs. 1, 3,) which temper the clay as the 5 shaft revolves.

M, is the bed plate fitted at the bottom of the clay box F. It is stationary and represented in various positions in the drawings, and may have any suitable number of 10 perforations, corresponding however to the molds which pass on the railway beneath it. In the center of this bed plate M, the shaft J, is stepped, and as the bed plate is only about one and a fourth inches thick, I have added 15 a hub so as to make the entire depth through for the step about three inches. If the shaft was stepped into this hub without any other appliances, the two metals which are always surrounded by sand and water, would cut 20 and wear away directly. To prevent this I enlarge the hub, and having perforated it to about five inches in diameter, I fill the opening with wood into which the shaft J, is to be stepped, and in order to make the 25 wood fast, and prevent its being forced through, I make the opening of the hub conical, the wood itself being the inverted frustum of a cone.

If the screw D, were seated on top of the 30 hub, it would have a space of two inches between the lower flange of the screw and the surface of the bed plate. In such case the molds would not fill. It is necessary that they should sweep as near together, without 35 contact, as possible. I therefore form a cavity or recess in the lower part of the screw, so as to inclose the hub within it, and this brings the lower flange of the screw within half an inch of the surface of the bed 40 plate, as seen in the several figures.

Fig. 4, is a top view of the bed plate and screw. Fig. 5, is a vertical central section through the same, showing the projecting hub a, the conical seat b, filled with wood, 45 the stem c of the screw D, the step e, for the shaft J, and the screw with its lower edge or flange close to the surface of the bed plate.

N, are the mold frames (Fig. 7); each mold has a separate or sliding bottom v, 50 which rest upon flanges x, placed at the inner lower edges of the mold—these plates also serve as a bottom to the clay box F. The molds are moved upon the ways O, and pass directly under the bed plate M, where they 55 are filled by the operation of the screw D, as before mentioned.

S, is a box with a reticulated wire bottom filled with dust, and hung on hinges. A shake of this box serves to dust the molds. 60 (Fig. 10 represents the dust box.)

In front of the bed plate M, is fastened a plate g, regulated by set screws to scrape the surface of the molds, and as this does not entirely remove it, a second plate, or broad 65 knife T (Figs. 2, 3, 9), hung on pivots at the

back corners which regulates itself by its own weight, and this slices off the surplus clay from the surface of the molds.

As the molds pass from under the broad knife, they are brought immediately over the pistons h h (Figs. 2, 7,) set in a frame or cross bar U, the ends of which fit in grooves in the legs V, V. Underneath the cross bar, are cams W, W, hung upon a shaft X, which has a lever H (Figs. 1, 2, 3) attached to it 70 at one end. By operating the lever the cams will raise the cross bar and with it the pistons, and the pistons in turn acting on the plates or bottoms v, lift the brick out of the molds; the plates and brick are then passed 75 onto a car or barrow, wheeled to the drying floor, and there set on edge to dry, in the act of doing this, the plates drop off, and are brought back to be returned to the empty 80 mold.

Fig. 8, shows a mold frame of different construction—it has no sliding bottoms, but one plate K', extending across the machine from rail to rail, and forming a bottom for the whole frame. The flanges m, m extend 85 below the sides of the mold so as to embrace the plate, and all move along the ways together. The mold itself is lifted off and borne to the yard, leaving the plate K', to be returned to the ways at the back of the machine. When the mold is thrown on the 90 ground, the brick does not come immediately on the ground, as in other molds, because the flanges intervene which are about an inch broad. This gives a concussion to the brick, 95 just enough to give it a start, and it then slips from the mold with ease.

Motion is given to the molds in the machine by means of the rock shaft and levers, as represented in Figs. 1, 3, as follows. The 100 eccentric Y, on the upper part of the shaft J communicates by the rod n, with the lever p, which is attached to a rock shaft, having its bearings r, in brackets f, attached to the frame A. Said rock shaft has two levers L 110 below it, containing a roller t between them at their lower extremities which acts against the molds, and forces them along the ways, by means of the vibrating rock-shaft, which alternately moves the whole train of molds 115 and leaves room to place an empty mold on the ways. If it were not for the roller, the motion of the lever in describing the arc of a circle, would lift the molds off from the rail, and the turning of the roller prevents this. 120

Having thus fully described the nature of my invention what I claim therein as new and desire to secure by Letters Patent is—

1. The flat, square, or triangular bar for pulverizing the clay, substantially as described. 125

2. I also claim in contradistinction from a metallic step, a step composed of wood and iron combined, substantially as, and for the purpose, above set forth and described. 130

3. I also claim the open portable mold frame with a projecting flange, said mold resting on a single detached plate for a bottom, and so that when the mold is thrown 5 on the floor, the brick does not at the same time come in contact with the ground because the flanges interfere—the concussion being just sufficient to give it a start, when it slips easily afterward from the molds, substantially as described.

F. H. SMITH.
